UNITED STATES PATENT OFFICE.

HARRY A. PETERS, OF VICTORIA, BRITISH COLUMBIA, CANADA.

STAMP-HINGE APPLICATOR.

Application filed June 18, 1919. Serial No. 305,081.

To all whom it may concern:

Be it known that I, HARRY A. PETERS, a citizen of the Dominion of Canada, residing at Victoria, in the Province of British Columbia, Canada, have invented certain new and useful Improvements in Stamp-Hinge Applicators, of which the following is a specification.

This invention relates to a device for applying to the sheets of an album or the like the gummed paper hinges by which postage stamps are fastened thereto.

It comprises a magazine within which the hinges, folded as used, are packed and from which they are delivered one at a time as required; also in combination therewith a means for moistening the paper of the sheet to which one part of the folded hinge is to be applied. The device also comprises the means for applying that part of the hinge to the moistened sheet for pressing it into adhering contact therewith and thereafter moistening the other part of the hinge to which the stamp is to be applied.

The invention is particularly described in the following specification, reference being made to the drawings by which it is accompanied, in which:

Fig. 1 is a perspective view of the hinge magazine detached.

Fig. 2 is a perspective showing the under side of the delivery plate of the magazine.

Figs. 3 and 4 show in perspective two different forms of hinge.

Fig. 5 is a similar view of the hinge delivery plate of the magazine modified to suit an alternate form of hinge.

Fig. 6 is a vertical section of the device complete on the line 6—6 on Figure 8, the 40 dot and dash lines indicating the position after just moistening the paper.

Fig. 7, a similar view showing the means by which the magazine is inverted, the dot and dash lines and arrows indicating the 45 turn-over movement.

Fig. 8, a plan, and

Fig. 9 is a vertical section on the line 9—9 on Figure 8 showing the action of the roller by which the gummed paper hinge is pressed 50 into adhering contact with the sheet to which it is applied.

Fig. 10 is a perspective view of the water reservoir and its wick tube as detached from its magazine.

The magazine comprises a thin metal box 55 2, rectangular in cross section, and of a size adapted to receive the gummed hinges 3 as folded for application. The front 4 of this box is removable and is apertured as at 5 to afford a view of the charge of hinges within 60 the magazine. The front 4 is connected to the sides of the magazine in any convenient manner, as by the upturned edges of the end cover 7 which is also removable, and at the other end by downwardly turned portions 8 65 from the aperture of the delivery plate 9. The front 4 and end plate 7 are removable to facilitate charging of the magazine, and the delivery plate 9 to enable that plate to be changed to suit different forms of stamped 70 hinges.

The hinges 3 in general use are of two forms as illustrated in Figs. 3 and 4. The commonest form illustrated in Fig. 3 is uniform in width and is folded unequally, 75 whereas that shown in Fig. 4 is equally folded but one of the folded portions is of reduced width. The plate 9 is apertured to correspond with the inside dimension of the magazine 2 and has projections 10 from the 80 front and back edges of the aperture, that will retain the larger part of the folded hinge as illustrated in Fig. 3 and will permit the edge of the smaller folded portion to project as shown from the delivery aperture 85 of the magazine.

Where the hinge illustrated in Fig. 4 is to be used the aperture of the delivery plate has the projections 10 from the sides of the aperture to permit that portion of the hinge 90 which is of reduced width to project.

The delivery plate 9, which is of very thin sheet metal, may be removably secured to the end of the magazine in any approved manner. It is here shown as having portions 11 cut and downwardly bent from the sides of the aperture which will exercise a resilient hold of the sides of the magazine while the end of the magazine is stopped against the inward projections 10.

The magazine is charged with the folded gummed hinges and these hinges are held

against the retaining projections 10 of the delivery end by a light coiled spring 12 between a bearing plate 13 in contact with the charge of hinges and the end 7 of the magazine, the smaller portion of the folded hinges being all turned toward the delivery end with their free edges toward the apertured front 4.

Removably secured to the back of the magazine, see Fig. 6, is a small water reservoir 14 having a wick tube 15 inserted in an aperture provided for it through which aperture the reservoir may be filled. This wick tube projects backward from the magazine at approximately the level of its delivery plate. The reservoir is removably connected to the magazine in any convenient manner. In the drawing it is shown as having side plates 16 to exercise a resilient grip on the magazine sides and a small stop plate 17 locating its position. The locating stops 17 may be cut and bent outward from the sides of the magazine. This manner of attachment enables the position of the reservoir to be angled to project the moistening wick in the tube 15 that it will just wipe the surface of the paper to which the hinge is to be applied.

The device by which the folded hinges are applied to the paper comprises a stationary frame composed of a top plate 20 with two supporting side plates 21 downwardly bent from it. The lower ends of these side plates 21 are connected together by cross ties 22 which are angular in cross section with the angles directed upward and inward. These cross ties afford an effective bearing on the paper to which the stamping device is applied and incidentally form a guard for the protection of a part of the mechanism to be described later. The outer corner of one or both of them may be rounded, as shown, for a purpose to be also explained later.

Secured to and upwardly projecting from the centre of the top plate 20 is a guide stem 23 on which is endwise movable a hollow plunger 24 between which and the end of the guide stem 23 is a coiled spring 25 by which the plunger is normally maintained at the upper limit of its movement. The lower end of the plunger 24 is secured to connecting members 26 which extend laterally outward and are turned down the outer side of each side frame 21 and receive the trunnions 27 of a turn-over plate 28 which trunnion pins are constrained to move vertically in elongated slots 29 in each side plate 21.

Downwardly projecting from each end of the turn-over plate 28 are portions 30 which are provided with notches 31 on each side of a heart-shaped portion 32. The notches 31, during downward movement of the turn-over plate, engages pins 33 inwardly pro-

jecting from each side plate 21, by which engagement the turn-over of the plate 28 on the trunnions is effected as the plunger 24 is pressed down.

The magazine 2, 4 is inserted from the upper side through an aperture in the turn-over plate 28 and is removably retained therein in any convenient manner, say by the downwardly bent ends 34 of the delivery plate 9 of the magazine through slots cut in the turn-over plate, which downwardly turned ends will exercise a resilient hold in the edges of the slots. When the magazine is so placed in the turn-over plate the outer end of the wick tube 15 attached to the magazine is so located that the moistened wick projecting from the end of the tube wipes across the surface of the paper on which the frame is placed as the back edge of that plate has just passed the first half of its turn-over movement and moistens the surface of the paper to which the latter part of the movement applies the free edge of the end hinge 3 projecting from the delivery end of the magazine.

The applied edge of the gummed paper hinge is pressed into adhering contact with the moistened surface of the sheet by a small roller 35 mounted on a wire axle 36 secured to the mid-portion of a cross bar 37 which extends across between the free ends of two levers 38 pivoted at 39 on each side frame 21. This cross bar and its roller 35 is normally maintained at the outer limit of its movement, where it is protected by one of the base cross ties 22 by a light spring or springs 40 secured to the side frame and bearing against the edge of the lever. The levers 38 are curved across the lower ends of the slots 29 of the side supports where they will be engaged by the lower ends of the trunnion pin-connections at the lower limit of their movement and will move those levers to draw the small roller 35 in between the applied edge of the paper hinge and the delivery plate 9 of the magazine. The resilience of the roller connection will thus press the applied edge of the hinge into adhering contact with the previously moistened sheet.

As pressure on the plunger 24 is relaxed and the delivery end of the magazine is withdrawn the other part of the applied hinge is withdrawn from the magazine and the moistened wick is wiped across the gummed face of the upwardly projecting last withdrawn portion of the folded hinge, so that a stamp may be immediately applied to it, if so desired, or if it is desired to apply a series of hinges to a sheet before applying the stamps thereto, the stamping frame may be tilted on one of the rounded corners of the base ties 22 to avoid moistening the free face of the hinge.

As the folded hinges packed within the

magazine and under pressure of the spring 12 may lose to some extent the springy tendency to open at the fold a spring 41 is secured to the underside of the top plate 20 and projects backward and downward therefrom into contact with the delivery plate 9 of the magazine. The free end of this spring, when the magazine is in the normal position, is adjacent the back edge of the 10 delivery aperture and its resilience tends to hold it below the level of that plate when the magazine is overturned, so that after one hinge has been withdrawn and as the magazine returns to its normal position, the face 15 of the magazine plate 9 is moved past the free end of the spring and will engage the free edge of the end hinge and open it clear of the plate so as to be ready for the next application.

20 It must be noted that the end plate 9 of the magazine is of very thin metal, so that the edge of the spring will catch the free edge of the hinge even if it is close folded against the other part. The turn-over plate 25 is cut away as at 42 to clear the end of the spring 41.

The use of a magazine wherein these gummed paper stamp hinges are folded ready for application and from which they 30 may be withdrawn one at a time as required effects alone a convenient improvement on the present manner of applying such hinges, and by mounting this magazine in a frame with a mechanism that will apply the hinges one at a time to the surface of a sheet with provision for moistening the paper of the sheet before such application the work is further simplified.

Having now particularly described my invention, I hereby declare that what I claim 40 as new and desire to be protected in by Letters Patent, is:

1. In an apparatus of the class described, a supporting framework, a turn over plate 45 mounted in said framework, means for turning over said turn over plate, said turn over plate having an aperture, a label holding magazine pendently held in the aperture of said turn over plate, means cooperative with said turn over plate for moistening the part to which the label is to be attached and other means cooperative with the turn over plate for applying the label from the magazine 50 to the moistened surface.

55 2. In an apparatus of the class described, a supporting framework, a turn over plate mounted in said framework, means for turning over said turn over plate, said turn over plate having an aperture, a label holding 60 magazine pendently held in the aperture of said turn over plate, means cooperative with said turn over plate for moistening the part to which the label is to be attached and other means cooperative with the turn over plate 65 for applying the label from the magazine

to the moistened surface, said magazine comprising a rectangular tube open at both ends and having one side removable, a delivery plate secured over one end of said tube, a cover removably secured over one end of the 70 tube, means carried by said delivery plate and said cover for holding said removable side in place, substantially as shown and described.

3. A stamp hinge magazine comprising an 75 elongated body of rectangular cross section adapted to receive the gummed paper hinges folded to have one folded portion smaller than the other, a cap closed at one end of said body and removably held thereon, a delivery plate removably held on the other end of said body through which the contents of said body passes, said delivery plate having inturned lugs to fit on said body and having projections from the opposite sides 80 of the aperture of said delivery plate so as to retain within the magazine, the larger folded part of the end hinge and permit the free edge of the smaller part to project, said means having a removable side retained 85 in place by said cap and said delivery plate and provided with a side aperture to afford a view of the charge within the magazine and means continuously tending to feed the contents of the magazine toward the discharge end.

4. A stamp hinge magazine, comprising an elongated chamber of rectangular cross section adapted to receive the gummed paper hinges folded to have one folded portion smaller than the other, said magazine being closed at one end and having a delivery aperture at the other end with projections from the opposite sides of the aperture that will retain within the magazine 100 the larger folded part of the end hinge and will permit the free edge of the smaller portion to project, a light spring between the closed end and the hinges within the magazine, and a water reservoir removably connected to the magazine and provided with a wick tube delivering upward and outward adjacent the delivery aperture of the magazine at approximately its level.

5. A stamp hinge magazine adapted to hold a series of gummed paper hinges folded to have one folded portion smaller than the other with a delivery aperture at one end with projections from the opposite sides of the aperture that will retain within the magazine 115 the larger folded part of the end hinge and will permit the free edge of the smaller folded part to project, means for pivotally mounting this magazine in a supporting frame with its delivery aperture normally 120 upward, means for inverting the magazine to apply the projecting portion of the end hinge to the surface on which the supporting frame stands, means operative by inversion of the magazine for moistening the 125 130

surface to which the hinge is applied prior to such application, and means operative upon reversion of said magazine for separating one portion of the exposed hinge from 5 the other.

6. A stamp hinge magazine adapted to hold a series of gummed paper hinges folded to have one folded portion smaller than the other with a delivery aperture at one 10 end with projections from the opposite sides of the aperture that will retain within the magazine the larger folded part of the end hinge and will permit the free edge of the smaller folded part to project, means for 15 pivotally mounting this magazine in a supporting frame with its delivery aperture normally upward, means for inverting the magazine to apply the projecting portion of the end hinge to the surface on which the 20 supporting frame stands, means operative by inversion of the magazine for moistening the surface to which the hinge is applied prior to such application, means co-operative with further inversion of the magazine 25 for pressing the applied outer part of the end hinge into adhering contact with the surface to which it is applied and means operative upon reversion of said magazine for separating one portion of the exposed hinge 30 from the other.

7. A stamp hinge magazine, comprising an elongated chamber of rectangular cross section adapted to receive folded gummed paper hinges having one folded portion smaller 35 than the other, said magazine being closed at one end and having a delivery aperture at the other end with projections from the opposite sides of the aperture that will retain within the magazine the larger folded part of the end hinge and will permit the free edge of the smaller portion to project, a light spring between the closed end and the hinges within the magazine, a water reservoir connected to the magazine and provided 40 with a wick tube delivering upward and outward adjacent the delivery aperture of the magazine at approximately its level, means for pivotally mounting the magazine within a suitable supporting frame with the delivery aperture normally upward, means for 45 inverting the magazine to wipe the surface on which the support rests with the moistened wick of the reservoir and thereafter applying to the moistened surface the free 50 edge of the hinge projecting from the aperture, means for pressing the applied edge of the hinge into adhering contact with the moistened surface, and means for restoring 55 the magazine to its normal position where- 60 by the applied hinge is withdrawn from the magazine.

8. A stamp hinge magazine, comprising an elongated chamber adapted to hold a series of gummed paper hinges folded to have 65 one folded portion smaller than the other,

with a delivery aperture at one end of the magazine with projections from the opposite sides of the aperture that will retain within the magazine the larger folded part of the end hinge and will permit the free edge 70 of the smaller folded part to project, means for pivotally mounting this magazine in a supporting frame with its delivery aperture normally upward, means for opening the projected smaller portion of the hinge angularly from the delivery face of the magazine, means for inverting the magazine to apply the projecting portion of the end hinge to the surface on which the supporting frame stands, and means operative by inversion of the magazine for moistening the surface to which the hinge is applied prior to such application.

9. A stamp hinge magazine adapted to hold a series of gummed paper hinges folded to have one folded portion smaller than the other with a delivery aperture at one end with projections from the opposite sides of the aperture that will retain within the magazine the larger folded part of the end hinge and will permit the free edge of the smaller folded part to project, means for pivotally mounting this magazine in a supporting frame with its delivery aperture normally upward, means for inverting the magazine to apply the projecting portion of the end hinge to the surface on which the supporting frame stands, means operative by inversion of the magazine for moistening the surface to which the hinge is applied prior to such application, means for restoring the magazine to its normal position whereby the remainder of the applied hinge is withdrawn from the magazine, and means operative by such restoring movement for moistening the surface of the last withdrawn portion of the applied hinge.

10. A paper hinge magazine comprising a container closed at one end and open at the other end and adapted for receiving paper hinges folded to have one portion smaller than the other and in superimposed relation, a delivery plate held over the open end of said container, said delivery plate having a discharge opening with projections for engaging the larger folded part of the hinges to retain the hinges within the magazine with the free edge of the smaller folded part of the hinges projected beyond the open end of the magazine, a device within the magazine continuously tending to move the hinges toward the open end, substantially as shown and described.

11. A stamp hinge magazine adapted to hold a series of gummed paper hinges folded to have one folded portion smaller than the other and having a delivery aperture at one end with projections from the opposite sides thereof that will retain within the magazine the larger folded part of the end 125

hinges and will permit the free edge of the smaller part to project, means for pivotally mounting the magazine in a supporting frame with its delivery aperture normally upward, means for inverting the magazine to apply the projecting portion of the end hinge to the surface on which the supporting

frame stands, and means for positively causing an uplift of the uppermost smaller portion of the hinge, as the magazine resumes its normal or return position. 10

In testimony whereof I affix my signature.

HARRY A. PETERS.
